UNITED STATES PATENT OFFICE.

ABEL KLEINSTIVER, OF PETROLIA, ONTARIO, CANADA, ASSIGNOR OF ONE-HALF TO B. S. VAN TUYL, OF SAME PLACE.

THRASHING AND SEPARATING MACHINE.

SPECIFICATION forming part of Letters Patent No. 429,135, dated June 3, 1890.

Application filed June 29, 1889. Serial No. 316,114. (No model.)

To all whom it may concern:

Be it known that I, ABEL KLEINSTIVER, a subject of the Queen of Great Britain, and a resident of Petrolia, in the county of Lambton, in the Province of Ontario, Canada, have invented certain new and useful Improvements on Thrashing and Separating Machines, of which the following specification, taken in connection with the accompanying drawings, forms a full, clear, and exact description.

This invention relates to a machine for thrashing and separating grain from impurities; and it consists of the improved construction and combination of parts of the same, as will be hereinafter first fully set forth and described, and then pointed out in the claims, reference being had to the accompanying drawings, wherein—

Figure 1 is a side elevation of a thrashing-machine embodying my invention. Fig. 2 is another side elevation of same, looking at the machine from the opposite side to that shown in Fig. 1. In this view the straw-carriers are removed and a chaff-conduit is shown in its extended position. Fig. 3 is an enlarged longitudinal sectional view of the machine on the line $x\ x$ of Fig. 4. Fig. 4 is a plan view of the straw-decks. Fig. 5 is a cross-sectional view of the machine on the line $a\ a$ of Fig. 3. Fig. 6 is a plan view of one of the chutes, showing grain and tailing conduits. Fig. 7 is a plan view of the screen, and this view also shows part of the grate-bars underneath. Fig. 8 is a side elevation of the thrashing-cylinder, showing the upper tooth-bar in section. Fig. 9 is a cross-sectional view on the line $b\ b$ of Fig. 8.

A designates the thrashing-cylinder, constructed of disks a' , rigidly secured to the shaft a^2 , and in these disks a' toothed bars a^3 are rigidly secured; and in these toothed bars a^3 sockets or holes a^4 are formed, one or more of the sides of which sockets a^4 incline inwardly, as shown in Fig. 8.

a^5 designate the teeth, the shanks of which are inclined or wedge-shaped on one or more sides to engage with the inwardly-inclined sides of the sockets a^4 . The teeth a^5 are placed in position in the sockets a^4 . They are then rigidly held therein by keys a^6 and set-screws a^7 or other suitable securing device.

B designates the concave, in which teeth are secured, the same as described in the thrashing-cylinder; and B', a grate or perforated extension of the concave B; and B² are 55 fingers extending from the grate B' underneath the drum-cylinder C.

C designates a drum-cylinder revolving on the shaft C', and this drum-cylinder C is provided with teeth C², which, as the cylinder C 60 revolves, pass between the fingers B².

D designates a straw-deck suspended by hangers D' from the frame of the machine, and this straw-deck D is formed with openings D², and is provided with prongs or fingers D³ and D⁴.

E is a straw belt or carrier situated below the straw-deck D and constructed of endless belts or bands e', of chain or other suitable material, and slats e² are secured to these 70 belts or bands e', and raking-teeth e³ are secured in the slats e². These belts or bands e' pass over and under and are supported by the pulleys e⁴ e⁵ e⁶ and eccentric-pulley e⁷, as shown in Fig. 3, and these pulleys e⁴, e⁵, and 75 e⁶ are supported by and revolve perfectly free on suitable bearings secured in the supplemental frame F, and the eccentric-pulley e⁷ is rigidly secured to the shaft F', and the latter is supported by and revolves perfectly 80 free in bearings secured to the main frame of the machine; or the pulleys e⁵ and e⁶ may be dispensed with, the object of using them being to give a greater fall or drop to the straw, and thereby increasing the separation. 85

The supplemental frame F is supported near one end by the eccentric-pulley e⁷, but the latter revolves perfectly free in said frame, and this frame F is also suspended by a hanger F² from the frame of the machine. 90

F³ designates a connecting-bar which connects the hanger F² with an extension of the rear hanger D'.

F⁴ is a directing-board, and F⁵ an inclined grain-deck which conduct the grain to the 95 cleaning-screen H, and this directing-board F⁴ and grain-deck F⁵ are rigidly secured to the supplemental frame F, and the grain-deck F⁵ is formed with inclined openings f⁶.

G is a chaff-conduit secured at one end to 100 the supplemental frame F, near the end of the grain-deck F⁵, and is suspended near its

outer end by a hanger g' from the main frame of the machine.

H is a cleaning-screen secured to the supplemental frame F in the position shown in Fig. 3, and a plan view of this screen is shown in Fig. 7.

H' is a grating situated below and adjacent to the screen H. This grating H' is supported in any suitable bearings in or secured to the supplemental frame F, and may be adjusted to any position under the screen H and held there by any suitable securing devices for the purpose of reducing the size of the openings in the screen H, so as to adapt the one screen to different sizes and kinds of grain.

I is a chute, and I' is a grain-conduit, which conduct the grain into the scourer.

I² is a deflecting-board pivotally secured near its center in the conduit I' to conduct the grain to either end of said conduit, as required.

I³ is a chute for catching the tailings, which are conducted by the conduit I⁴ to the elevators K. The conduits I' and I⁴ extend in an angular direction across the machine for the purpose of facilitating the delivery of the grain therefrom. These chutes or conduits I, I', I³, and I⁴, screen H, and adjustable grate H', grain-deck F⁵, and directing-board F⁴ are secured to the supplemental frame F by connections f⁷, and are agitated as the supplemental frame F is operated. This agitation of these parts causes the grain and tailings to deliver freely therefrom.

K' are fingers which bridge the space between the screen H and the chaff-conduit G for the purpose of conducting any short straws falling thereon to the chaff-conduit G.

The scourer N consists of a shaft n', provided with helical curved blades n², as shown in Fig. 5, and these blades n² revolve in a cylindrical casing n³.

L is a fan situated in the fan-cylinder L' and operated in any suitable manner, and M is a wind-regulator in the exit-opening of the cylinder L.

The sheaves are fed to and pass between the cylinder A and concave B, where the grain is beaten out, the greater portion of which 50 grain falls through the grate B' and onto the grain-deck F⁵, which delivers it to the screen H. The straw and the remaining portion of the grain pass over the grate B' and onto the fingers B², and as they pass over the latter 55 the straw is picked apart by the teeth C² of the drum-cylinder, which permits the grain to fall onto or through the straw-deck D.

When the machine is in operation, motion is communicated to the shaft F', as well as to 60 the eccentric-pulley e⁷, rigidly secured thereon, and as the longer radius of the eccentric-pulley e⁷ revolves from the pulleys e⁴, &c., they, as well as the supplementary frame F, to which they are secured, are moved toward the 65 rear of the machine, and this supplemental frame F is balanced on the hanger D', so that at each revolution of the eccentric-pulley e⁷

a reciprocating motion is imparted to the straw belt or carrier E and supplemental frame F, as well as to the directing-board F⁴, 70 grain-deck F⁵, screen H, grate H', chaff-conduit G, and grain-chutes and conduits I, I', I³, and I⁴, secured to said supplemental frame F. At the same time the endless bands e' of the straw belt or carrier E revolve over 75 and with the pulleys e⁴, e⁵, e⁶, and e⁷, which gives a combined reciprocating and revolving motion to the straw belt or carrier E. As just mentioned, the supplemental frame F is balanced on the hanger F², thereby not 80 only effecting a large saving in the wear of the machine, but the machine will operate effectively with less power than another not balanced, as just described. As the supplemental frame F and hanger F², supporting 85 the same, is operated, a backward and forward motion is imparted to the straw-deck D by the connecting-bar F³, connecting the hanger F² with the rear hanger D', supporting said straw-deck D, and agitates the straw 90 and grain thereon, so that as the straw passes off the fingers B² onto the straw-deck D as the latter rises and falls in its backward and forward movement the raking-teeth e³ of the straw belt or carrier E, as well as the prongs 95 or fingers D³, not only further pick the straw apart, but carry it toward the rear of the straw-deck D. The straw and grain are agitated by the straw-deck D until they fall off the prongs or fingers D⁴ onto the straw-deck 100 E, which completes the separation of the grain, the straw, being held by the teeth e³, passes over the straw belt or carrier E at the rear of the machine, and the grain falls onto the directing-board F⁴, to be conducted to the 105 screen H. As the grain falls onto and through the openings in the grain-deck F⁵, screen H, and grate H', the blast created by the fan L not only keeps the openings cleared, but blows the chaff and light impurities onto the chaff-conduit G, which delivers them at the back 110 of the machine. The grain falls through the screen H and grate H' onto and is conducted by the chute I and conduit I' to the scourer 115 N, through which it passes, and wherein the fuzz, &c., is removed. It then passes out of the scourer N through a spout to a receptacle placed in position to receive it. Any un-thrashed heads of grain passing over the end of this screen H and through the fingers K' 120 are conducted by the chute I³ and conduit I⁴ to the elevator, which elevates and carries them back to the cylinder to be further thrashed.

Having thus described my invention, I 125 claim—

1. The combination of the supplemental frame F, supported on the eccentric-pulley e⁷ on the shaft F' and hanger F² and the main frame, with the straw belt or carrier E, and 130 pulleys e⁴, e⁵, and e⁶, substantially as shown and described, and for the purpose set forth.

2. The straw-deck D, having openings D² formed therein, prongs or fingers D³ and D⁴,

hangers D', and connecting-bar F³, in combination with the supplemental frame F, supported on the eccentric-pulley e⁷ on the shaft F' and the hanger F², the main frame, the straw belt or carrier E, and the pulleys e⁴, e⁵, and e⁶, substantially as shown and described, and for the purpose specified.

3. The combination of the supplemental frame F, supported on the eccentric-pulley e⁷ on the shaft F', and the hanger F², and the main frame, the straw-deck D, hangers D', and connecting-bar F³, the straw belt or carrier E, directing board F⁴, grain-deck F⁵, the

screen H, adjustable grate H', the chutes I, I', I³, and I⁴, and the deflecting-board I², all 15 secured to and operated by the supplemental frame F, substantially as shown and described, and for the purpose specified.

In testimony whereof I affix my signature in the presence of the two undersigned witnesses.

ABEL KLEINSTIVER.
